US0D1035000S

(12) **United States Design Patent** (10) **Patent No.:** **US D1,035,000 S**
(45) **Date of Patent:** **** Jul. 9, 2024**

(54) **ULTRASONIC DIAGNOSTIC APPARATUS**

(71) Applicant: **CANON MEDICAL SYSTEMS CORPORATION**, Otawara (JP)

(72) Inventors: **Sakiko Tanimoto**, Tokyo (JP); **Satoshi Shinata**, Kanagawa (JP); **Takahiro Yamamoto**, Kanagawa (JP)

(73) Assignee: **Canon Medical Systems Corporation**, Otawara (JP)

(**) Term: **15 Years**

(21) Appl. No.: **29/839,397**

(22) Filed: **May 20, 2022**

(30) **Foreign Application Priority Data**

Jan. 19, 2022 (JP) ..... 2022-000844 D

(57) **CLAIM**

The ornamental design for an ultrasonic diagnostic apparatus, as shown and described.

DESCRIPTION

FIG. 1 is a top, front, right perspective view of an ultrasonic diagnostic apparatus, shown in a first configuration with the display open and the keyboard closed;

FIG. 2 is a front elevation view thereof;

FIG. 3 is a rear elevation view thereof;

FIG. 4 is a top plan view thereof;

FIG. 5 is a bottom plan view thereof;

FIG. 6 is a left-side elevation view thereof;

FIG. 7 is a right-side elevation view thereof; and,

FIG. 8 is a right-side elevation view of the ultrasonic diagnostic apparatus of FIG. 1, shown in a second configuration with the display folded for clarity of disclosure.

The equal-length broken lines in the photographs depict portions of the ultrasonic diagnostic apparatus that form no part of the claimed design.

1 Claim, 8 Drawing Sheets
